UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

Original application filed April 3, 1919, Serial No. 287,132. Divided and this application filed January 24, 1923. Serial No. 614,591.

To all whom it may concern:

Be it known that I, WINTHROP K. HOWE, a citizen of the United States of America, residing at Rochester, in the county of Monroe and State of New York, have invented certain new and useful Improvements in Automatic Train-Control Systems, of which the following is a specification.

This invention relates to automatic train control systems, and more particularly to the means for communicating from the track to the train the necessary and proper controlling influences.

One of the essential features of any system of train control is an efficient and reliable means for establishing communication between the train control apparatus on the locomotive, or control means therefor, and the traffic controlled elements along the track, which are subject to control by the presence of other trains or dangerous conditions ahead, such that the necessary controlling impulses or influences required to control the operation of the train control apparatus on the locomotive may be effectively transmitted whenever dangerous conditions demand. Such means of communication between the track and a train should, it is believed, be one which acts inductively, that is, without any physical contact between any parts on the track and any parts on the train; and one of the principal objects of this invention is to provide a simple and reliable construction and arrangement of parts capable of transmitting controlling influences by electro-magnetic induction in such a way that the operation of the system will not be affected by weather conditions and can be arranged to operate satisfactorily with various clearances, types of rolling stock, and other practical working conditions.

In communicating from the track to the train inductively it is believed expedient to employ as a track device an inert magnetic element, that is, a magnetic body which does not require electrical energy to maintain it in its active or its inactive condition. One form of train control apparatus to co-

type comprises a core of suitable iron having a magnetizing winding and having suitable electro-responsive devices associated therewith, whereby when this core passes over an inert track element along the track comprising a dead mass of magnetic material when in its active condition, the track element will change the flux through the magnetic circuit of the car element on the vehicle, thereby inducing an electro-motive-force which will affect the electro-responsive device associated therewith.

In order to make this inert track element ineffective to produce operation of said electro-responsive device, a winding is provided on the track element which may be closed upon itself by suitable controlling devices whereby a choking effect is produced by the winding. When a magnetized car element passes over the track element with its winding closed upon itself, the flux through the magnetic core of the car element will not be changed appreciably, that is, a very slight change of flux through the track element will induce a current in the track element winding causing a magneto-motive-force which will counteract the magneto-motive-force of the car-carried element, in consequence of which very little magnetism will link the two elements, and the electro-responsive device on the train will not be operated.

The advantage of an inductive communicating system of this kind is that no source of electrical energy is required for each track element along the track resulting in economy, especially when primary batteries are used, and which makes a device which operates on the side of safety because an open circuit in the winding will cause an automatic actuation of the apparatus carried on the train, whereby the train will be controlled. One of the disadvantages and difficulties of an inductive communicating system of this kind is the effect produced on the car-carried devices by other magnetic bodies, such as crossing rails, switch frogs, or the like, which produce a similar action on the train carried element, and although feeble, may under certain conditions cause

automatic control of the train. For convenience the effect of such foreign magnetic bodies along the track will be referred to as rail interferences throughout this specification.

With the above and other considerations in mind, the principal object and purpose of the present invention is to provide a car-carried device which is constructed and arranged in a manner not to be influenced by foreign magnetic objects, such as rails, frogs, etc., but which will be influenced by comparatively short magnetic objects properly placed along the track, such as the inert track elements of magnetic material heretofore mentioned.

Other specific objects and features of this invention will appear hereinafter as the description progresses, and the novel features of the invention will be pointed out in the appended claims.

For the purpose of disclosing my invention I have illustrated in the accompanying drawings in a simplified and diagrammatic way some of the various forms which the devices embodying my invention may take, this illustration being selected more with a view to make it easy to understand the construction, operation and characteristic features of a system embodying my invention, rather than with a view of showing the exact construction of parts preferably used in practice.

In describing the several modifications of my invention in detail, reference will be made to the accompanying drawings, in which:—

Fig. 1 shows diagrammatically one arrangement of the trackway circuits which may be used in the train control system embodying my invention.

Fig. 2 shows a car-carried element which is constructed not to be improperly influenced by the track rails of a crossing, and one form of track element which is to cooperate therewith;

Fig. 3 illustrates another construction and arrangement of parts for preventing the car-carried element being improperly influenced by the track rails of the crossings;

Fig. 4 illustrates a modified form of the trackway device which includes a battery;

Fig. 5 illustrates another construction and arrangement of parts for preventing the car-carried element being improperly influenced by the track rails of crossings, cross-overs, and the like, in which the main car-carried element is the same as shown in Fig. 3; and

Fig. 6 illustrates a system like that shown in Fig. 5, except that the car-carried element as shown in Fig. 2 has been substituted for the main car-carried element.

This is a division of my prior application, Serial No. 287,132, for automatic train con-

trol system, filed April 3, 1919. In describing several embodiments of the present invention, several forms of inert track elements will be described in connection with a well-known arrangement of track circuits and control devices for controlling the actuation of said track elements.

The trackway element T consists essentially of a U-shaped core or yoke 45 (see Fig. 2), having pole pieces 46 and two coils 47 wound on the yoke below the pole pieces 46 in the same direction with respect to the core, or in other words, so that the voltages due to a change of flux in the core will be cumulative. This yoke 45 and pole pieces 46 are made of iron or other magnetic material, solid or laminated as conditions require. The pole pieces 46 are preferably disposed on the level, or just above the top of the heads of the track rails, so as to be as close as possible to the car-carried element and yet be out of the way of all parts of the rolling stock. The trackway element T is given different controlling conditions, that is, is rendered capable of influencing or not influencing the car-carried element on a passing vehicle, by putting the coils 47 in an open circuit or in a deenergized closed circuit of low resistance. While the circuit of the coils 47 may be controlled in any suitable way, I have illustrated in Fig. 1 one form of trackway circuits suitable for governing the controlling condition of the trackway element T in accordance with traffic conditions.

Referring to Fig. 1, the track rails 48 are divided by insulated joints 49 into blocks in the usual way, one block B with the adjacent ends of two other blocks A and C being shown. The parts and circuits associated with the various blocks A, B and C are the same, and for convenience will be given like reference characters with distinctive exponents. Each of the blocks is provided with a track battery and a track relay 50, the same as the ordinary block signaling systems. Since my system of automatic train control is preferably used in connection with the usual fixed signals of the well-known automatic block signal system, such signals are indicated conventionally in Fig. 1; but the circuits and devices for controlling the indications and aspects of these fixed signals, being well-known in the art, have not been illustrated in order to avoid unnecessary complication.

At a suitable distance in the rear of the pair of insulated joints 49 at the entrance of each block is located the trackway element T (the normal direction of traffic being from left to right, as indicated by the arrow); and the circuit for the coils 47 of said trackway element is controlled by the contact finger or armature of a line relay 51, the controlling circuit of which includes

front contacts of the track relays of the corresponding block and the next block in advance. For example, the line relay 51 controlling trackway element T at the entrance of the block B is energized when neither the block B nor the block C is occupied, but is deenergized to open the circuit for the coils 47 when either of said blocks B or C is occupied.

10 The particular form of trackway circuits shown in Fig. 1 is merely illustrative of the manner in which the trackway elements of my system are controlled in order to transmit a cautionary impulse at each caution signal, and not transmit such a cautionary impulse at a clear signal. Obviously, various modifications and alterations may be made in the particular trackway circuits illustrated, it being evident that various expedients may be employed to assure the opening or closing of the circuit for the coils 47 of the trackway element T at signaling points, depending upon traffic conditions in advance. Generally stated, the characteristic feature of the trackway circuits employed in my system of train control is that the coils 47 of the trackway element are in closed circuit at a clear signal, but are open-circuited at a caution signal. In the trackway circuits shown in Fig. 1, the coils 47 of the trackway element are likewise open-circuited at a stop or danger signal, but this is not compulsory.

15 The car-carried element suitable for operating with the trackway element T may take various forms, some of which have been shown. In the construction shown in Fig. 2, the car-carried element L is constructed in a manner not to be affected when the car on which it is mounted passes over track rails and other foreign magnetic bodies. In this construction there are two inverted U-shaped yokes X and X¹ connected at their middle points by a crossbar W, preferably of smaller cross-section than the legs of said yokes X and X¹, for the purpose hereinafter explained.

20 The legs of the yokes X and X¹ are each provided with pole pieces 95 and a coil, as 96, 97, 98 and 99. The two pole pieces on the innermost adjacent legs of the yokes X and X¹ are located at the proper distances apart to pass over the pole pieces 46 of the trackway element T shown; and the coils 97 and 98 on these legs are wound so that their voltages add when a change of flux occurs through the path including the coil 98, crossbar W, and coil 97. The coils 96 and 99 are wound with respect to each other so that their voltages add when a change of flux takes place through the magnetic path through coil 96, bar W, and coil 99, but are so connected with the coils 97 and 98 that their voltages oppose the voltages of 97 and 98 when a change of flux through the two

25 paths above referred to takes place simultaneously. The coils 96, 97, 98 and 99 are connected in series in circuit with a battery 102 and the control relay R. On the legs of the crossbar W are field coils 100, which 70 are constantly energized from a battery 101 through a circuit including the winding of a check relay 56. The check relay 56 and the control relay R govern the operation of an electro-pneumatic valve E. P. V., which 75 is adapted to slow down or stop the train in any suitable manner. This check relay 56 is a relay of any suitable or well-known construction, which is capable of dropping its armature 57 upon a predetermined reduction in the amount of current flowing through it to assure safe and proper operation of the system, which requires that the field coils 100 be energized and creating sufficient flux to insure inducing of current in 80 the coils 97 and 98 when the car passes an open-circuited trackway element.

85 The relay R comprises a coil 61 adapted to energize and attract a bar-armature or operating element 60, which is pivotally supported and provided on its opposite end with a striking piece 70 of insulating material, and is disposed between contact springs 71 and 71¹ which normally bear against contact points 72. The spring 66 is 95 so adjusted that when the magnet 61 of the relay is energized by a normal current, the contact springs 71 and 71¹ are both in contact with their respective contact points 72, the armature 60 being in a balanced position. The striking piece 70 is preferably made slightly shorter than the space between the contact springs 71 and 71¹, in order that the armature 60 may have a slight movement from its middle balanced position before acting against said contact springs. It will be evident that a decrease in the normal current through the magnet 61 will permit the spring 66 to over-balance the attraction of the armature 60, thus separating the bottom contact spring 71¹ from its contact point 72. If the current through the magnet 61 is increased above that normally flowing, and for which the relay is adjusted, the attraction of the armature 60 100 over-balances the opposition of the spring 66, thereby separating the other cooperating contacts 71 and 72. The circuit controlled by the relay R passes from one contact spring 71 through the contact points 72 105 to the other contact spring 71¹, as indicated. Thus, whenever the current for which the relay is adjusted is either increased or decreased, the circuit controlled by the relay 110 will be opened.

115 The circuit for normally energizing the E. P. V. may be traced as follows:—Commencing at the battery 74, wire 75, contacts 71—72—71¹ of the control relay R, wire 76, contact finger 57 of the check relay 56, 120

wire 77, magnet 17 of the E. P. V., and wire 78 back to the battery. The safe and proper operation of the system requires that the field coils 100 must be energized and creating sufficient flux to result in inducing current in the secondary coils 97 and 98, when the car passes an open-circuited trackway element, in the manner more fully explained hereinafter in the description of the operation. The check relay 56 insures the integrity of the circuit for energizing the field coils 100, since this relay will open its contacts whenever the current in this circuit falls below a predetermined value, due to the breaking of the circuit or depreciation of the battery 101. An excessive current in the field coils 100 will only serve to increase the inducing action, at least within narrow limits depending upon the design of the magnetic circuits and coils; and consequently, the check relay 56 may properly be a minimum current device.

In order to afford protection against crosses, short circuits, or the like, in connection with the energizing circuit for the field coils 100, the check relay should be similar in construction to the balanced type of relay R heretofore described. In a similar way the control relay R checks the integrity of its circuit through the secondary coils 96, 97, 98 and 99, since any break or cross of the wires, or depreciation of the battery 102, results in opening the contacts of said control relay, due to the increase or decrease in the current normally flowing, and for which said relay is adjusted. Thus, the balanced type of relay R not only acts as a device for detecting the current induced in the secondary coils 97 and 98 under dangerous traffic conditions, but also insures that the current normally flowing in this circuit will be maintained within the narrow limits required for satisfactory operation.

If an ordinary relay, operating upon a minimum current, were put in the circuit for the secondary coils 97 and 98 for the purpose of detecting the current induced in said coils, it is evident that the current normally flowing through such relay should not be much in excess of the dropaway current; otherwise, the induced voltage might not be strong enough to reduce the normal current sufficiently to cause such a relay to drop away. Therefore, the use of a balanced type of relay, such as relay R shown, has the advantage that it simplifies the system by combining in one device the requisite functions of a checking and a detecting relay. Further, the construction of the relay R will cause a stopping of the train if the battery voltage should be a little too high, this stopping action being due to the effect of the second-half of the cycle of the impulse received from the track ele-

ment, which is in a direction to add to the voltage of the battery 102, thereby causing sufficient current to flow to attract the armature 60 and separate the contacts 71¹ and 72.

The operation of my inductive device for transmitting influences from the track to a passing vehicle, according to the construction shown in Fig. 2, is as follows:— When the car-carried element L passes over the track element T, such as shown in Fig. 2, and the coils 47 of said trackway element T are open-circuited, the flux through the secondary coils 97 and 98 is greatly changed to induce a current therein. If the crossbar W is made of such cross section as to be substantially saturated, the effect is increased, because with normal current flowing in the coils 100, an increase in the flux through the coils 97 and 98 necessarily results in decreasing the flux through the coils 96 and 99, thereby inducing a voltage in these coils due to a decrease of flux; and since the coils 96—99 are wound oppositely to the coils 97—98 when considered in a magnetic circuit through these coils and the crossbar W, the voltage induced due to a decrease of flux through the coils 96 and 99 will add to the voltage induced due to an increase of flux through the coils 97 and 98, the path of flux in each instance being through the crossbar W. These induced voltages modify the current normally flowing through the winding of the control relay R, and cause it to open its contacts and operate the E. P. V.

If now the car-carried element shown in Fig. 2 should pass over a track rail of a crossing, the flux through each of the four coils 96, 97, 98 and 99 will be changed, that is, increased substantially alike; and since the coils 96 and 99 are wound oppositely to the coils 97 and 98 with respect to the magnetic paths through these coils and the crossbar W, the voltages induced therein will neutralize each other, thereby producing no operation of the control relay. The pole pieces of the car-carried element are preferably so located with reference to the trackway that the track rails of crossings, and the like ordinarily encountered, will influence the flux through these pole pieces substantially the same; and in any event, so that the effect of such a track rail will be neutralized to such an extent that no operation of the control relay will occur.

If a railway vehicle equipped with the car-carried apparatus shown in Fig. 2 passes over a track element in a manner to assume the cooperating relation, as shown in Fig. 2, and the coils 47 of the trackway element are closed in a circuit of low resistance, no such control influence will be transmitted. This is attributed to the opposition or "bucking action" of the current induced in the closed circuited coil 47 of the trackway element T

and prevents material change in the flux through the crossbar W and the legs containing coils 97 and 98.

In Fig. 3 has been shown a modification 5 of the construction of the car-carried element shown in Fig. 2. In this modified construction, the field coils 100 are omitted and a single cross member or yoke W¹ connects the cores or legs upon which the combined 10 field and secondary coils 96¹, 97¹, 98¹ and 99¹ are mounted. In view of the previous discussion of the operation of the car-carried element shown in Fig. 2, the operation of 15 this modified construction will be evident without further explanation.

In the various modified constructions hereinbefore considered, the trackway element T is changed from the clear to the caution controlling condition by open-circuiting its 20 coils. This arrangement has the advantage that no energy is required along the track to control the trackway element and change it from a caution or stop to a clear controlling condition. This is a matter of considerable 25 importance where the sources of current available along the trackway, such as the primary batteries used for the block signaling system, cannot be practically used to supply any great amount of current for any 30 prolonged time. If desired, however, the trackway element may be placed in condition so as not to influence the car-carried element on a passing train, by supplying current to its coils, as the coils 47, to magnetize the yoke of said trackway element with a polarity opposite to the polarity of the crossbar W of the car-carried element. Such a construction is shown in Fig. 4, in 35 which the coils 47 of the trackway element T are energized from a battery 104, or other 40 source of current, when the line relay 51 is picked up.

Another arrangement for preventing an 45 impulse being improperly transmitted at crossings, crossovers, and the like, is shown in Fig. 5. In this arrangement, there are two car-carried elements M and N. The car-carried element M is shown constructed the 50 same as that illustrated in Fig. 3; and the car-carried element N comprises a U-shaped core provided with coils 80 connected in circuit with a relay R¹ similar to the relay R, and a battery 55. A change in the reluctance 55 of the magnetic circuit through the core will cause a momentary change of current in the circuit through the relay R¹, thus opening the contact 71 or 71¹ depending upon the direction of the induced voltage with respect to the voltage of the battery 55.

Between the track rails 48 and in position 60 to cooperate with the two inner cores of the car-carried element M, is a trackway element T, the same as that shown in Fig. 2. At one side of the trackway element T, preferably on the outside of one of the track

rails, is disposed a mass of iron O, preferably U-shaped, which is arranged to cooperate with the pole pieces of the car-carried element N. The control relays R¹ and R, governed by the car-carried elements N and M, respectively, have their contacts included 70 in two multiple branches of the controlling circuit for the E. P. V., so that the contacts of both of these control relays must be simultaneously operated before the E. P. V. 75 is deenergized. The control relay R¹ is operated at each signaling point, irrespective of traffic conditions, since the mass of iron O always induces current in the coils of the car-carried element N. The control relay R 80 is operated at the signaling points under dangerous traffic conditions, but is not operated under clear traffic conditions. Consequently, the E. P. V. is operated or not operated at the signaling points depending 85 upon traffic conditions in advance.

If all of the pole pieces of the car-carried element M simultaneously pass over a magnetic body, as the track rail of the right-angle crossing (indicated at 105, Fig. 5), the 90 control relay R is not operated for the reasons hereinbefore explained in connection with the discussion of the construction shown in Fig. 3. When the track rail of a crossing or crossover extends at an angle 95 across the main track rails, the successive influencing of the cores of the car-carried element M may, under certain adverse circumstances, cause operation of the control relay R; but the angular position of the track rail 100 required to do so is such that the car-carried element N will be influenced either at some time later or at some time earlier during the passage of the car, so that both of the control relays R and R¹ are not simultaneously 105 operated. For example, a track rail, as 106, positioned at such an angle that it may cause operation of the control relay R, will not influence the trackway element N and operate the control relay R¹ until after the car- 110 carried element M has moved beyond the influence of said track rail and the control relay R is closed.

If the track rail of the crossing or crossover is disposed at another angle, as indicated at 107, the relay R¹ will be operated first, and then perhaps the relay R. In any event, the E. P. V. is not operated. If conditions should arise where several foreign bodies of iron along the trackway are 120 located with respect to the track in substantially the same manner as the track elements O and T, one of these elements may be modified by building magnetic material adjacent the same in a manner to cause a 125 change of flux early enough not to open one of the relays R and R¹ at the same time the other of said relays is open.

A system substantially the same as that shown in Fig. 5 has been illustrated in Fig. 130

6. The distinguishing feature of this system over the one shown in Fig. 5 resides in the employment of the car-carried element and associated parts shown in Fig. 2 to constitute the car-carried element M instead of the car-carried element and associated parts shown in Fig. 3.

In view of the detailed discussion of the operation of Fig. 5, which is substantially 10 the same as the system shown in Fig. 6, it is believed unnecessary to describe the operation of the system shown in the latter figure in detail. It may, however, be stated that the car-carried element M of Fig. 6 15 acts upon the relays 56 and R, the same as does the device L of Fig. 2, and the elements N and O are the same and function the same as the elements N and O of Fig. 5.

It should be noted that the operation of 20 the system is dependent upon the functioning of devices which have well recognized dependability. The reliable performance of track circuits and various other parts of automatic block signaling systems has 25 been thoroughly established by long trial and experience, and the influence transmitting means and automatic train control apparatus of my system likewise consists of simple devices capable of accurate performance. Thus, without undue complication and expensive apparatus, I have provided 30 a system in accordance with my invention which will obviate, to a large extent, if not entirely, the occurrence of accidents upon 35 railways and one that will be operated only by track elements when they are in their active condition.

In disclosing my invention I have selected 40 simplified forms of construction, it being understood that various amplifications and modifications in accordance with good design and engineering practice would be made in the specific construction shown and described when putting my invention to 45 practical use. For instance, the car-carried element L would be firmly secured to some appropriate part of the frame or running gear of the locomotive, motor car or other railway vehicle, and would be placed in a 50 suitable casing to protect it from the weather.

The particular location and manner of 55 supporting this car-carried element would vary upon different equipments, but in all cases an ample clearance of four or more inches above the level of the tops of the track rails could be readily provided, so that the car-carried element would not be struck or injured by the track rails at crossings, and the like, or by other similar projections usually encountered along railways. It will be evident that the distance of the car-carried element above the track rails will 60 vary as the wheels of the vehicle wear down, or are replaced by new wheels; and I con-

template the provision of suitable means for adjusting the car-carried element vertically to compensate for such variations.

The trackway element is fastened securely in any appropriate manner to the ties of 70 the track, either between or outside of the track rails according to which arrangement is best suited to the conditions of the particular installation, and this trackway element would be preferably housed and 75 protected against dragging objects on passing trains by a planking or housings of wood, or some non-magnetic material. The trackway element may be located at any 80 desired point along the track where it is required to transmit a cautionary impulse to passing vehicles, and may be located at the approach to sharp curves, or other fixed hazards, as well as adjacent to the fixed signals of the block signaling system. 85

With the arrangement of trackway circuits shown in Fig. 1, the trackway element may be located at any point with reference to the entrance of a block, providing it is in the rear of the insulated joints at the 90 entrance of the block, so that the vehicle will not stop itself by entering the block and putting the trackway element in its caution controlling condition. It will be evident, however, that if a different arrangement of trackway circuits is used, in which the trackway element at the entrance to a block is not controlled by the track relay of that block, the various trackway elements may be placed in advance of the fixed signals if circumstances make it desirable to do so. The control relay R and the E. P. V. would be placed in practice in a suitable casing or cabinet on the vehicle and protected from jar and vibration by spring supports, 95 or the like.

The various parts of the system may be sealed or locked to prevent unauthorized or malicious tampering with them; and recorders and other well-known devices may be 100 used in connection with the system to check up the care and vigilance used by the engineer. In short, various additions and modifications, obvious to those skilled in the art, may be made in the particular construction 105 shown and described without departing from my invention; and I desire to have it understood that the specific constructions and arrangement of parts and circuits shown and described are merely illustrative of my 110 invention, and do not exhaust the various modifications of the idea of means constituting my invention. 115

What I claim as new and desire to secure by Letters Patent of the United States, is:— 120

1. In an automatic train control system, the combination with a car-carried element of an electro-magnetic impulse transmitting means comprising, a partial magnetic circuit and coils adapted to be influenced by 125

- non-magnetized magnetic bodies along the track, another partial magnetic circuit and coils adapted when influenced by non-magnetized magnetic bodies along the track to neutralize the influence in the first mentioned coils, of traffic controlled trackway elements arranged to influence the first mentioned coils but not the other coils under danger traffic conditions ahead.
2. Car equipment for automatic train control systems of the type in which controlling influences are communicated by magnetic cooperation between devices on the trackway and devices on the vehicle moving thereon comprising, a yoke having extending legs and having oppositely wound coils on two of said legs, a circuit connecting said coils in series, and automatic train control means responsive to a change in the current in said circuit.
3. A car element for the inductive impulse transmitting means of train control systems provided with two oppositely wound coils and partial magnetic circuits therefor, a source of magneto-motive-force for supplying flux to said partial magnetic circuits, a track element adapted to complete the partial circuit through one but not both of said coils, and train control means having an operating circuit connecting said coils in series.
4. A car element for inductively controlling automatic train control systems comprising working means and neutralizing means each adapted to be influenced by magnetic bodies along the track respectively operating therewith, and a traffic controlled track element acting when in the acting stopping condition to influence said working means but not the neutralizing means, said working means and neutralizing means being arranged to be both influenced by magnetic track rails disposed crosswise of the running rails.
5. In a train control system, a magnetic yoke carried on a car and provided with two partial magnetic circuits, a source of magneto-motive-force for supplying flux to said circuits, electro-responsive train control means on the car, oppositely wound coils associated with said magnetic circuits, said electro-responsive means being operated when one but not both of said partial magnetic circuits is completed, and a track element acting when in the stopping condition to complete one but not both of said partial circuits, said partial magnetic circuits being arranged to cause a track rail extending crosswise of the running rails to influence both of them.
6. A car-carried element having a working partial magnetic circuit and a neutralizing partial magnetic circuit, trackway means acting to influence the working partial circuit but not the neutralizing partial
- circuit, train control means, electro-responsive means influenced by a change of flux in the working partial circuit for causing operation of said apparatus, and means associated with the neutralizing partial circuit for preventing operation of said apparatus when both of said partial circuits are completed by a track rail or other magnetic body along the track.
7. In a train control system of the type in which the controlling impulses are communicated from the track to moving vehicles by exchange of magnetic flux and in which a partial magnetic circuit on the car is completed by track elements in their active stopping condition, the combination with said partial magnetic circuit, of electro-responsive means operable by a change of flux therein, another partial magnetic circuit on the car, and means operable upon a change of flux in said another partial circuit for preventing operation of said electro-responsive means, whereby impulses will not be improperly communicated by the track rails or other magnetic bodies on the track affecting both partial circuits.
8. In a train control system car equipment comprising a source of magneto-motive-force, two partial magnetic circuits including said source, train control apparatus, control means responsive to a change of flux in said two partial magnetic circuits for governing said apparatus, said control means acting to cause operation of the apparatus when one but not both of said circuits is completed by magnetic bodies on the track, and traffic controlled trackway elements constituting in the stopping condition a partial magnetic circuit cooperating with one but not both of the car-carried partial circuits.
9. In an automatic train control system, the combination with train control means on a car set into operation by magnetic bodies on the track of limited extent but not operated by bodies of larger extent, of track elements constituting in the stopping condition a magnetic body of such limited extent, and traffic controlled means for opposing the passage of flux through said track element under safe traffic conditions.
10. In an automatic train control system, the combination with automatic train control means on a car rendered active by magnetic bodies extending part way across the track but not all of the way, of track elements comprising a magnetic yoke extending part way across the track and having a winding thereon, and traffic controlled means for opening and closing a deenergized circuit of low resistance through said winding.
11. In an automatic train control system, the combination of car carried apparatus including a train control device, two partial

- magnetic circuits each having a coil associated therewith, a normally energized electro-responsive device for governing said train control device connected in a circuit 5 in series with said coils, and of trackway means controlled in accordance with traffic conditions ahead and comprising a non-magnetized body of iron when in its active condition for inductively producing a voltage in one of said coils but not in the other coil upon passage of the train thereby under danger traffic conditions ahead, said coils being connected in series so that simultaneous changes in fluxes therethrough due 10 to simultaneous passage over a non-magnetized magnetic body produces counter-acting voltages in said circuit.
12. Car-carried apparatus for automatic train control systems comprising, a normally energized train control device, two separate normally energized electro-responsive devices each of which if energized alone maintains said train control device energized, a separate inductive influence communicating device for each of said electro-responsive devices, each of said influence communicating devices including a coil located in inductive relation with the trackway and adapted to have a potential induced therein upon the passage of the train by a suitable trackway device, whereby said train control device is actuated only if inductive control influences are received by both of said electro-responsive devices 15 simultaneously.
13. In a train control system, the combination of a track divided into blocks, inductive influence communicating means at each control point including a plurality of track elements each element of which comprises a mass of inert and unmagnetized iron when in its active influence transmitting condition, and car-carried apparatus comprising two influence receiving coils located to simultaneously cooperate with said track elements upon the passage of the train by a control point and each of which is adapted to have a voltage induced therein by reason of a car-carried source of magneto-motive-force when passing by a track element, and a normally energized electro-responsive device which is deenergized only if a voltage is induced in both of said influence receiving coils simultaneously, 20 whereby said electro-responsive device is not actuated if a foreign magnetic body induces a voltage in one of said influence receiving coils only.
14. In an automatic train control system, the combination of an influence receiving means on a vehicle including a car element of limited extent and adapted to transmit a control influence when passing over magnetic bodies of limited extent but not transmitting a control influence when passing over 25
- magnetic bodies of a larger extent having a flux producing coil for producing a field of flux which is necessary to transmit such control influences, an electro-responsive device connected in circuit with said flux producing coil which if deenergized will cause an application of the brakes, said device having a dropaway characteristic so that it will assume its deenergized position when the current in said flux producing coil falls so 30 low that insufficient flux will be present for transmitting control influences, a trackway element constituting a magnetic body of the same limited extent, and traffic controlled means for opposing the passage of flux through said track elements under safe traffic conditions.
15. In an automatic train control system, the combination with a track element constituting a partial magnetic circuit when in the stopping condition, of an engine element comprising a yoke having extending legs, oppositely wound coils on two legs of said yoke and connected in series, both of said coils being subjected to substantially the same influence when the engine element passes over extraneous magnetic bodies along the track, only one coil being under the influence of the regular track elements, and electro-responsive means on the engine 35 connected to said coils.
16. In an automatic train control system, the combination of car-carried apparatus including a train control device, two partial magnetic circuits each having a magneto-motive force induced therein and a coil associated therewith, a normally energized electro-responsive device for governing said train control device connected in a circuit in series with said coils, and of trackway means controlled in accordance with traffic conditions ahead and consisting of a non-magnetic body when in its active condition located to inductively produce a voltage in one of said coils but not in the other coil 40 upon passage of such vehicle thereby under danger traffic conditions ahead, said coils being connected in series so that simultaneous changes in fluxes therethrough produces counter-acting voltages in such circuit, whereby voltages induced in said coils, due to the passing of magnetic bodies of considerable length and influencing both of said coils, neutralize each other.
17. In an automatic train control system, the combination of car carried apparatus comprising, an electro-responsive device, an inductive influence receiving device located so as to inductively communicate with magnetic bodies along the trackway having coils associated therewith connected to said electro-responsive device, said inductive device and coils being correlated so that said electro-responsive device is actuated if a short magnetic body is passed over but is not ac- 45

5 tuated if a magnetic body of greater extent than said inductive device is passed over, and a traffic controlled trackway device comprising, a short non-magnetized magnetic body, when in an active condition for actuating said electro-responsive device under danger traffic conditions ahead.

10 18. Car carried apparatus for automatic train control systems comprising, a core of magnetic material having four coils associated therewith, a source of magneto-motive-force acting upon said core, an electro-responsive device, a circuit including said electro-responsive device and said coils in series so that a change of flux in all of said coils due to said magneto-motive-force upon passing over a bar of magnetizable material produces counter-acting voltages in said circuit, whereby said electro-responsive device 20 is actuated if a change of flux in certain of said coils only is effected by the passage of

said core over a magnetic body of limited length.

19. In an automatic train control system the combination of car carried apparatus including two normally energized electro-responsive devices each having a normally closed contact which is opened if the current for energizing the same is either increased or decreased, two separate inductive influence receiving elements each having a coil connected to one of said electro-responsive devices, a train control device having a winding, and a circuit for energizing said train control device, including in series a source of energy, the winding of said train control device, and a partial circuit including the two contacts of said electro-responsive devices connected in multiple.

25 30 35 In testimony whereof I hereby affix my signature.

40 WINTHROP K. HOWE.
